[57] **CLAIM**

The ornamental design for a clamp for closing flexible hoses of infusion, transfusion medical equipment, as shown and described.

DESCRIPTION

FIG. 1 is a perspective view of a clamp for closing flexible hoses of infusion, transfusion medical equipment and shows our design;

FIG. 2 is a left side view of the clamp for closing flexible hoses of infusion, transfusion medical equipment;

FIG. 3 is a front elevational view of the clamp for closing flexible hoses of infusion, transfusion medical equipment;

FIG. 4 is a plan view from above of the clamp for closing flexible hoses of infusion, transfusion medical equipment;

FIG. 5 is a plan view from below of the clamp for closing flexible hoses of infusion, transfusion medical equipment; and,

FIG. 7 is a right side view of the clamp for closing flexible hoses of infusion, transfusion medical equipment.
